UNITED STATES PATENT OFFICE.

LOUIS GOODMAN, OF DUBUQUE, IOWA.

DESIGN FOR A SHAVING AND DRESSING STAND.

53,363.

Specification for Design.

Patented May 27, 1919.

Application filed March 20, 1918. Serial No. 223,667. Term of patent 7 years.

To all whom it may concern:

Be it known that I, LOUIS GOODMAN, a citizen of the United States, residing at Dubuque, in the county of Dubuque and State of Iowa, have invented a new, original, and ornamental Design for a Shaving and Dressing Stand, of which the following is a specification, reference being had to the accompanying drawing, forming part thereof.

The figure is a perspective view of the shaving and dressing stand, showing my new design.

I claim:—

The ornamental design for a shaving and dressing stand, as shown.

LOUIS GOODMAN.
